UNITED STATES PATENT OFFICE.

HAYO FOLKERTS, OF AACHEN, GERMANY.

CONVERTER.

Application filed February 16, 1924. Serial No. 693,363.

To all whom it may concern:

Be it known that I, HAYO FOLKERTS, a citizen of Germany, residing at Aachen, No. 48 Rutscherstrasse, Rhenish Prussia, 5 Germany, have invented certain new and useful Improvements in Converters; and I do hereby declare the following to be a full, clear, and exact description of the invention, such as will enable others skilled in the art 10 to which it appertains to make and use the same.

This invention relates to converters employed in the steel practice, and it has for its primary object to provide a converter 15 permitting of large and controllable quantities of blast being fed to the metal bath or converter shaft evenly throughout the entire cross-section of the converter and at the smallest possible expenditure of energy, 20 and further permitting of attaining at the exit of the blast nozzles an air velocity which, as the case may be, will be held to be the most preferable one with regard to the height of the bath, the duration of the 25 converting and the required properties of the product.

The said object, viz, the energetic and universal accommodation of the blast supply to the converting or working process, is 30 reached according to the invention by using short smooth nozzles which are preferably mounted interchangeably in a converter bottom solely formed by a metal plate which is cooled on the blast inlet side in such a 35 manner that, on the blast outlet or bath side which is exposed to high temperatures (more than 1000° C.) the temperature and consequently the oxidation of the respective face of the plate is kept in moderate 40 limits. The most suitable material for making the converter bottom is steel which is difficult to oxidize, for instance, stainless steel. In order to allow the converter bottom to be made thin and thereby render the 45 cooling action as efficient as possible, it is advisable to prop the bottom by staybolts or the like, such as for instance by nozzles constructed and arranged as staybolts.

The above and other objects of the 50 invention will be fully understood from the following description and the annexed drawings.

In the drawings:

Fig. 1 is a vertical section of the lower 55 portion of a converter with water cooling;

Fig. 2 is a similar section of a converter with blast cooling;

Figs. 3 to 10 are sections and plans, respectively, of a plurality of forms of nozzles, the sections showing also the connection of 60 the nozzles with converter bottom and the outer wall of the cooling jacket.

Referring now to the drawings, and more particularly to Fig. 1, *a* designates the converter bottom consisting of a metal plate. 65 This plate is constructed of material which will not appreciably melt or oxidize under the working conditions of the converter. Stainless steel is an example of a metal which satisfies the working conditions desired for use as a converter bottom for the purposes of this invention. Arranged at a short distance below the bottom *a* is a plate *b* which constitutes the outer wall of a water jacket formed by the two plates *a* 70 and *b*. *c* are the nozzles which extend through the plates *a* and *b*. The cooling jacket has connected to it a water supply pipe *b*¹ and a water outlet pipe *b*². Arranged underneath the plate *b* is the blast 75 box *d* with the blast inlet *d*¹.

With the embodiment shown in Fig. 2, the converter bottom *a* forms the top wall of the blast box *d* so that, in this case, the converter bottom will be cooled by the blast 80 flowing through the nozzles *c*.

The nozzles *c* may either lie with their axes parallel with the converter axis, as shown in Fig. 1, or their axes may extend radially with relation to the centre of the 85 sphere of which the converter bottom is a segment, as shown in Fig. 2. The latter arrangement possesses advantages both as regards the manufacture of the bottoms as well as the distribution of the blast in the 90 converter shaft.

According to Fig. 3 the converter bottom *a* is provided with simple non-interchangeable nozzles *c* which taper toward the converter shaft. These nozzles are adapted to 100 be used for baths of small height and a comparatively long duration of converting. The velocity of the air at the exit of these nozzles *c* is lower than the velocity of sound. The nozzle *c* shown in section in Fig. 4 and 105 in a top plan in Fig. 5 is interchangeable but of a shape similar to that of Fig. 3.

Fig. 6 shows a converter bottom carrying interchangeable nozzles *c* flaring out toward the converter shaft. With these nozzles the 110

blast velocity in the flaring portion is higher than the velocity of sound.

The interchangeable tapering nozzles *c* according to Figs. 7 and 8 are annular and provided with suitable baffle plates *e* for the purpose of obtaining a helical or whirling distribution of the blast.

The nozzles *c* illustrated in Figs. 9 and 10 are designed for use in converters with water cooling such as shown in Fig. 1. The nozzles according to Fig. 9 are in threaded engagement with the converter bottom *a*. They rest on the lower wall *b* of the water jacket by means of annular shoulders *f* and are securely held in the same by means of nuts *g* screwed on the outer threaded end of the nozzles and bearing against the wall *b* through the intermediary of yieldable rings *h* interposed between the nuts and the said wall. The converter bottom is thus supported by the nozzles on the wall *b*. Owing to the yieldable rings the nozzles have a limited play in axial direction. As a matter of course, the different conditions of elongation of the walls *a* and *b* due to changes of temperature are duly taken into account.

The nozzles *c* according to Fig. 10 are in threaded engagement both with the plate *a* forming the converter bottom and the plate *b*. The edges of the holes of the plate *a* receiving the threaded nozzle ends are rounded off at the outlet end. Besides, the cooling of the hole edges is rendered particularly efficient by providing the underside of the plate *a* with annular recesses *i* surrounding the screw holes.

The threaded portions are preferably made of the same dimensions for almost all diameters of nozzles that may come into question, so that nozzles with a relatively large diameter may be readily replaced by nozzles with smaller diameters.

Having thus described my invention, what I claim as new and desire to secure by Letters Patent, is:—

1. In a converter, a nozzle-carrying con-

verter-bottom consisting of a plate of non-oxidable steel.

2. In a converter, a nozzle-carrying converter-bottom consisting of a metal plate, another metal plate arranged underneath the first-mentioned plate at a certain distance from the same, a cooling jacket formed by the two plates, aligning holes in the plates, and the blast nozzles being mounted with their ends in the said holes so as to be adapted to be interchanged.

3. In a converter, a nozzle-carrying converter-bottom consisting of a metal plate, a cooling jacket formed by this plate and another metal plate spaced with relation to and arranged underneath the first-mentioned plate, aligning holes in the two plates for receiving and holding the ends of the blast-nozzles, the nozzles being mounted interchangeably and with a limited axial play in said holes and having bearing shoulders adapted to seat on the lower plate so as to drop the upper plate which constitutes the converter bottom.

4. In a converter, a nozzle-carrying converter-bottom consisting of a metal plate, a cooling jacket formed by this plate and another metal plate spaced with relation to and arranged underneath the first-mentioned plate, aligning holes in the two plates for interchangeably receiving and holding the ends of the blast-nozzles, the said first-mentioned plate having the edges of its holes rounded off at the outlet side of the nozzles and being provided on its lower face with cooling recesses concentrical with relation to the holes.

5. In a converter, a nozzle-carrying converter-bottom consisting of a metal plate, this plate having the shape of a calotte and the nozzles being arranged in the plate so that their axes extend radially with relation to the centre of the sphere of which the calotte is a section.

In testimony whereof I have signed my name to this specification.

HAYO FOLKERTS.
